No. 655,243.

Patented Aug. 7, 1900.

L. A. KEITH.
FUSE BLOCK.

(Application filed Sept. 11, 1899.)

(No Model.)

UNITED STATES PATENT OFFICE.

LORIN A. KEITH, OF MANSFIELD, OHIO.

FUSE-BLOCK.

SPECIFICATION forming part of Letters Patent No. 655,243, dated August 7, 1900.

Application filed September 11, 1899. Serial No. 730,143. (No model.)

To all whom it may concern:

Be it known that I, LORIN A. KEITH, a citizen of the United States, residing at Mansfield, in the county of Richland and State of Ohio, 5 have invented a new and useful Fuse-Block, of which the following is a specification.

This invention relates to fuse-blocks, and more particularly to the binding-plates thereof and means for attaching the fuse-wire to 10 the binding-plates; and it has for its object to provide a simple and efficient construction through the medium of which the clamping-washer will be given a longitudinal movement with respect to the clamping-screw to 15 clamp the end of the fuse-wire against the end of the binding-plate, the washer being held against rotary motion, and thus preventing the cutting of the fuse-wire, as is so often done when the clamping-surfaces have a sliding 20 movement with respect to each other.

A further object of the invention is to provide a simple and cheap construction of the parts of the device without impairing their efficiency.

25 This invention is applicable to all uses of the fuse-block, whether employed in connection with junction-boxes, rheostats, or any other specific apparatus.

In the drawings forming a portion of this 30 specification, and in which like reference-numerals indicate corresponding parts in the several views, Figure 1 is a perspective view showing a fuse-block having binding-plates fixed thereto and constructed in accordance 35 with this invention. Fig. 2 is a plan view of Fig. 1 on a larger scale. Fig. 3 is a central longitudinal section of Fig. 2, partly in elevation. Fig. 4 is a longitudinal section of a portion of a block, showing a modification.

40 Referring now to the drawings, 5 represents a block of porcelain, vulcanite, or other suitable insulating material upon which are mounted the binding-plates constructed and equipped in accordance with this invention. 45 These binding-plates 6 are arranged one at each end and upon the upper surface of the block and separated by an interspace. Each plate has a longitudinal slot 7 therein, the material from the slot being struck up at right 50 angles to the upper face of the plate to form an ear 8. Between the ear 8 and the inner end of the plate 6 is formed a perforation 9,

opening through the plate and into an annular recess 10 in the upper surface of the block 5 and concentric with the perforation. 55

A machine-screw 11 of any suitable material has a preferably-cylindrical head 12 disposed in the recess 10 and adapted for rotation therein, this screw having a stem 13, comprising a cylindrical portion lying in the perforation 9 and a threaded outer portion which projects above the upper surface of the plate 6, the upper end of the stem having a diametrical slot 14. Disposed upon the stem of the screw is a clamping-washer in the 60 form of a nut 15, the threads of which engage the threads of the stem, and which nut is adapted to travel longitudinally of the screw when the latter is rotated. In order to prevent rotary movement of the nut with the 65 screw, a radial slot 16 is formed in the nut and which slot is of a size to snugly receive the ear 8, and thus to hold the nut against rotation while permitting it to have sliding movement with respect thereto. 70

75 Adjacent the outer end of the plate 6 is formed a threaded perforation 17, adapted to receive a screw 18, having a frusto-conical head 19. At the sides of the plates 6 and adjacent the threaded perforation 17 are formed 80 upwardly-directed flanges 19^a, intermediate which and upon the upper face of the plate is disposed a channel-block 20, comprising parallel members 21 and 22, having a connecting-web 23, the screw 18 being passed through 85 a slot 24, formed longitudinally of this web.

In practice the terminals of the conductors with which the block is connected are inserted between the heads of the screws 18 and a member 21 or 22 of the block 20, after which 90 the screw is turned down through the plate 6 and clamps the terminal between the engaging surfaces, the channel-block having a sliding movement, so that it may automatically adjust itself and secure the best gripping action, a recess 25 being formed in the block 5 to receive the lower end of the screw. The nuts 15 are then raised by manipulation of the screws 11 and the ends of the fuse-wire are passed beneath the nuts and between 100 them and the plates 6, either outside of the ears 8, as shown, or between them and the screws. By then rotating the screws the nuts are fed downwardly upon the fuse-wire and

act to clamp it against the binding-plate, thus to hold it firmly in position and without cutting it. The plate 6 may be secured to the block 5 in any desired manner, and I have shown them attached by means of screws 26.

Referring to Fig. 4 of the drawings, there is shown a modification comprising a binding-plate 30, fixed upon an insulating base or block 31, the terminal of the conducting-wire 10 being held between the clamping-screws 32 and the upper surface of the plate 30, a flange 33 being formed at one side of the plate to prevent lateral displacement of the wire or conductor. In this construction a screw 35 and nut 36 are employed, the screw being passed through the plate and having its head disposed in a recess of the block in the same manner as above described. Instead of forming an ear upon the plate, however, a perforation 37 is formed therein in communication with a recess 38 in the block 31. An ear 39 is formed upon the nut 36 and extends outwardly therefrom and then downwardly at right angles thereto and enters this perforation and recess, the fit of the ear in the perforation being sufficiently snug to prevent rotation of the nut with the screw and to permit movement of the nut longitudinally of the screw.

30 The screw in each instance may have either a right or a left hand thread as desired; but it is preferred that they have left-hand threads in order that the nut will be moved into its clamping position when the screw is turned 35 to the right.

It will of course be understood that in practice any desired insulating material may be employed for the block and that any conductive material that is suitable may be employed for the other parts of the construction 40 and that the specific construction and proportion may be varied without departing from the spirit of the invention.

What I claim is—

45 1. A fuse-box comprising a base, a binding-plate fixed to the base, a screw rotatably mounted in the plate, a nut engaging the screw and adapted for movement upon the screw toward and away from the plate, and 50 means for preventing rotation of the nut.

2. The combination with a plate having a screw rotatably mounted therein, of a nut engaging the screw and adapted for movement thereon toward and away from the plate, and 55 means for preventing rotation of the nut.

3. The combination with a plate, of a screw passed therethrough and having a head lying at one side of the plate, a nut engaging the

screw upon the opposite side of the plate from the head, and means for preventing rotation 60 of the nut, said nut being movable upon the screw toward and away from the plate.

4. In a fuse-block, the combination with a member having a screw mounted therein, of a second member engaging the screw and adapted for movement thereon toward and away from the opposing member, an opening 65 in one of the members, and an ear upon the other member, entering the opening and movable therein and adapted to prevent rotation 70 of the second member upon the screw.

5. A fuse-block comprising a binding-plate having a screw rotatably mounted therein, an ear carried by the plate, and a nut engaging the screw and adapted for movement thereon 75 toward and away from the plate, said nut having a recess in which the ear is adapted to lie to prevent rotation of the nut.

6. The combination with a fuse-block having a recess therein, of a binding-plate fixed 80 to the block, a screw passed through the plate and having a head lying in the recess of the block, a nut engaging the screw and adapted for movement thereon toward and away from the plate, an ear carried by the plate and a 85 recess in the nut in which the ear is disposed to prevent rotation of the nut.

7. The combination with a binding-plate adapted for attachment of a fuse-wire thereto, of a screw engaged with the plate and having 90 a fixed frusto-conical head, and a channel-block having a slot therein through which the screw is passed, said block being movable transversely of the screw and being disposed to receive the head of the screw in its channel, whereby the screw may clamp the wire 95 between its head and the channel-block with a grinding action.

8. A wire-clamp comprising a screw having a fixed head the under side of which is tapered, and a channel-block having an opening 100 therein through which the screw is passed, said block being slidable transversely of the screw and arranged to receive the tapered portion of the head of the screw in its channel 105 to exert a gripping action between the tapered portion of the screw and the channel-block.

In testimony that I claim the foregoing as my own I have hereto affixed my signature in 110 the presence of two witnesses.

LORIN A. KEITH.
